ORE SEPARATOR

Nathan Goldberg, Denver, Colo.

Application November 19, 1931, Serial No. 576,046

1 Claim. (Cl. 210—149)

This invention relates to improvements in machines for separating metallic particles from nonmetallic particles or gangue and has reference more particularly to a machine for separating gold from auriferous sands and gravels.

It is well known that there exists in the arid parts of this and other countries immense deposits of sand and gravel that contain gold, but owing to the absence of water it has heretofore been impractical to properly treat these gold bearing sands and gravels so as to separate the metallic values from the nonmetallic ones.

It is the object of this invention to produce a machine of a simple construction that can be readily transported and which can be operated with a small amount of power, and, which in addition is so designed and constructed that the water that is used in its operation can be used over and over again and in this way it is possible to handle a large amount of material with a small amount of water, which adapts this machine especially for use in arid regions where water is scarce.

This invention, briefly described, consists of a supporting frame work whose lower portion is provided with a tank. A sluice is provided which is inclined from one end to the other and means is provided for depositing gravel and water at the upper end thereof. Located underneath the lower end of the sluice and directly above the tank is a riffle box. This riffle box is inclined in the direction of its length and is suspended from a rod located above in such a way that it can be rocked transversely. The riffle box is provided with transversely extending riffles. Located directly beneath the discharge end of the riffle box is a receptacle that is adapted to receive the discharge from the riffle box and this receptacle is provided with means for straining the material so that only the water passes through into the tank. The machine is provided with a pump which can be operated either by hand or by power derived from an engine and this returns the water to the upper end of the sluice. When the pump is operated the riffle box is rocked about its pivot by means of a crank and connecting rod.

Having thus briefly described the invention, the same will now be described in detail and for this purpose reference will be had to the accompanying drawing in which the preferred embodiment thereof has been illustrated, and in which:

Fig. 1 is a side elevation of the machine, parts being broken away to better disclose the construction;

Fig. 2 is an end elevation looking in the direction of arrow 2 in Fig. 1;

Fig. 3 is a section taken on line 3—3, Fig. 1;

Fig. 4 is a section taken on line 4—4, Fig. 3; and

Fig. 5 is a section through the tank showing the receptacle nested therein.

The machine that forms the subject of this invention consists of a frame work having parallel longitudinally extending angle irons 6 whose ends are connected by transverse angle irons 7. Extending upwardly from the two corners on one side are vertical supports 8 and on the other side correspondingly spaced vertical supports 9. The vertical supports 8 are somewhat taller than those designated by reference numeral 9 and have their upper ends connected by means of an angle iron 10. The upper ends of the shorter supports 9 are connected by means of an angle iron 11. A rectangular tank 12 is provided within the frame and rests on the inturned flanges of frame members 6 and 7. Angle irons 13 extend around the frame at the upper edge of the tank and serve to reinforce the latter. Angle irons 10 and 13 are connected on one side by means of a bar 14 to which a bracket 15 is secured. At one end of the frame a sheet metal plate 16 extends between the angles 10 and 13 and to this another bracket 15a is connected. Brackets 15 and 15a are provided with bearings in which the shaft 17 is journaled. One end of shaft 17 is provided with a crank disk 18 and the other with a pulley 19. The disk 18 has a crank pin 20 to which one end of the connecting rod 21 is connected. Secured to the plate 16 is a stub shaft 22 on which is mounted for rotation two pulleys 23 and 24. These pulleys are connected by a tubular hub 25 and are held against longitudinal movement by means of a washer 26 or other suitable means. The pulley 23 has been shown as provided with a handle 27 by means of which it can be turned manually. A belt 28 connects pulleys 19 and 24 in the manner shown in Figs. 1 and 2. Secured to the tank directly beneath the pulley 23 is a rotary pump 29. This is connected with the inside of the tank and the rotor shaft 30 is provided with a pulley 31 that is connected to the pulley 23 by means of a belt 32. A pipe 33 extends from the discharge port of the pump to a nozzle 34 that is connected with the upper end of the sluice. When the pump is operated, it will transfer water from the tank to the sluice 35 and this water will flow downwardly along the sluice in the manner which will be described hereinafter.

The sluice 35 is supported at its upper end on the outer end of a transverse frame member 36 and extends downwardly along the outside of the frame work where it is supported on the outer end of a frame member 37. After passing the member 37, the sluice curves through an angle of one hundred eighty degrees and is again supported by the frame member 37 as shown in Figs. 1 and 2. A rod 38 extends longitudinally of the frame

and is supported at its opposite ends by transverse frame members. Supported by rod 38 is a riffle box 39. This box has a substantially flat bottom portion 40 and upwardly and outwardly inclined sides 41. The bottoms and sides are pressed inwardly as shown in Fig. 4 so as to provide transverse riffles 42. The upper walls of the riffles are substantially perpendicular to the bottom and the lower walls are inclined. Attached to the sides 10 are supporting members having two arms 43 and 44. These arms come together at the top and are provided with a hook 45 that receives the rod 38. The bottom of the riffle box is provided with a pair of lugs 46 between which the 15 connecting rod 21 is pivoted. When shaft 17 is rotated, the crank reciprocates the connecting rod 21 and this in turn rocks the riffle box about the axis of the supporting rod 38. The riffle box is downwardly inclined, and its upper end is located 20 below the lower end of the sluice so that the material that is discharged from the sluice is deposited near the upper end of the riffle box. For the purpose of directing the material into the sluice, a hopper 46 has been provided. This is supported 25 by means of bars 47 whose lower ends are connected to the sides of the sluice. Located within the tank is a receptacle having triangular sides 48 and 49 and an end member 50. The sides and end members are connected by means of a bottom 30 51. A longitudinal section of the receptacle is a right angle triangle whose hypotenuse is substantially equal to the distance between the transverse frame members at the top of the tank. The upper end of the end member is provided with a 35 hook 52 and the other end of the base is provided with a corresponding hook 53. When the receptacle is in place it is supported by the two hooks in the manner shown in Fig. 1. When the machine is not in use, the receptacle can be placed 40 within the tank in the manner shown in Fig. 5. When the parts are in the position shown in Fig. 5 the inside of the tank can be used for storing the parts during transportation and shipment. The pump, belt, wheels, chute, riffle box, etc., are 45 removed during shipment and when placed inside of the tank produce a package that is convenient for handling. The end wall 50 and the lower end of the bottom are provided with openings 54 through which the water may flow from the 50 receptacle into the tank and in order to prevent the sand and gravel from clogging these openings, a spacer plate 55 is provided. The upper end of this plate is turned rearwardly as indicated at 56 and openings are provided which permit the 55 water to flow into the compartment 57.

Let us now assume that the machine has been constructed in the manner described and that the hopper 46 is filled with sand or gravel with which is mixed metal particles, such as gold. The pulley 23 is rotated either by hand or by means of an engine and this transfers water from the tank

to the upper end of the sluice. Gravel or sand from the hopper is deposited in the sluice and this is carried by the water and deposited in the riffle box near the upper end of the same. The riffle box is rocked transversely by the action of the crank and connecting rod and therefore the gangue and mineral matter are agitated whereupon the heavier particles gravitate downwardly and are deposited on the bottom of the riffle box and accumulate above the riffles. The water and gangue that is discharged from the riffle box falls into the receptacle where the water is separated and passes into the tank from which it is again removed by the pump and deposited at the upper end of the sluice, thereby using the water over and over again until it is exhausted. When the receptacle is filled with gangue material, it is emptied and the operation continued. Sand such as desert sand contains a large amount of gold of the type known as flour gold and this is so small that it is floated away by the water when the material is treated in the ordinary way. When treated by means of this machine any flour gold that may float away with the water will accumulate within the tank and by skimming the water from time to time, this flour gold can be saved.

I want to call particular attention to the riffle box employed in connection with this machine because it has been found to be exceptionally efficient and this efficiency is due to the shape 105 and the fact that it is rocked transversely about an axis located above the top of the sand.

Having described the invention what is claimed as new is:

In a device for separating valuable metals from ore and of the type in which the ore is passed over a riffle box and in which the water is separated from the ore and reused, means for separating the water from the ore comprising a storage tank of rectangular construction, and a receiving tank having two parallel sides of triangular shape, one angle of which is substantially ninety degrees, a bottom and one side, the side forming the hypotenuse of the triangular sides being the top, the bases of the triangular sides being somewhat shorter than the length of the storage tank and the width of the separating tank being somewhat less than the width of the storage tank whereby the receiving tank can be placed in the storage tank for shipment, the hypotenuse of the sides of the receiving tank being substantially equal to the length of the storage tank, means at ends of the receiving tank for supporting it from the ends of the storage tank, and a screen 110 in the lower portion of the end wall of the receiving tank for permitting water to flow from the latter into the storage tank while retaining the solid particles.

NATHAN GOLDBERG. 135
